DEVICE FOR LEVELING SHOE SOLES

John Tweedie, Jefferson City, Mo., assignor of
one-half to Charles Tweedie, Jefferson City,
Mo.

Application April 10, 1935, Serial No. 15,524

6 Claims. (Cl. 12—38)

My invention relates to means for leveling the soles of shoes, that is, to means whereby the stitching and lips of the channels are flattened down even with the adjacent surface of the sole 5 and whereby the front and heel portions of the sole are flattened and the intervening shank portion is given the proper convex curvature. Heretofore the common practice of leveling soles of McKay stitched shoes has been to pull the last, 10 insert an iron last in the shoe, apply a top form to the sole and then squeeze or press the sole between said iron last and the top form. This common method of leveling has several disadvantages, namely, it was expensive because it required a full quota of iron lasts and top forms 15 corresponding with the various styles, widths and sizes of shoes and because there was much delay in continually shifting such top forms and iron lasts which are quite heavy. Another disadvantage of the common practice is that the iron last cannot uniformly fit the shoe as well as the last 20 on which the shoe was lasted and the ill fitting of the iron last shows in the work after leveling.

Heretofore the common practice of leveling soles of Welt processed shoes has been to mount 25 the lasted upper with sole attached on the last in a leveling machine commonly known as a Goodyear leveler, which has a device which levels the bottom or sole with a pressure roll which 30 rolls the bottom smooth. This common method has several disadvantages, namely, the rolling process has a marked tendency to squash the toe box out of shape, is a slower method and does not produce a clearly defined shank and ball 35 line.

Heretofore the common practice of leveling soles of turn processed shoes has been to rub the bottom or sole smooth after the turned shoe has been relasted. This common method has several 40 disadvantages, namely, the rubbing process, done either by hammer rub, stick rub, or by power-propelled rolls with flattened surfaces, has not produced consistency smooth bottoms by reason of not reaching all of the surface at the same 45 time, and has little or no effect on smoothing or leveling the seam-ridge and lip on the inside of the shoe from inseaming the upper to the sole.

The principal object of the present invention is to produce a device for use in leveling shoes 50 which device will dispense with iron lasts and top forms and enable the leveling to be done with the shoe on the last on which it was lasted and which is used in subsequent operations under the McKay process above described, and which will 55 overcome the disadvantages under the welt proc-

ess above described, and which will overcome the disadvantages of the turn process above described, and which will be advantageous in leveling shoes under other processes of shoemaking. The invention consists in the device hereinafter 5 described and claimed.

In the accompanying drawing, wherein like reference numerals refer to like parts wherever they occur,

Fig. 1 is a plan view of my device with the metal 10 layer shown in dotted lines,

Fig. 2 is a longitudinal section on the line 2—2 in Fig. 1,

Fig. 3 is a cross-section through the shank portion on the line 3—3 in Fig. 1, 15

Fig. 4 is a view of the preferred form of metal layer,

Fig. 5 is a detail view of the extra metal toe section,

Fig. 6 is a view similar to Fig. 1 illustrating a 20 modification,

Fig. 7 is a view of the metal layer adjacent shank portion of the modification illustrated in Fig. 6,

Fig. 8 is a cross-section on the line 8—8 of 25 Fig. 6.

My device comprises a layer 1 of metal between two or more layers 2, 3 of leather or fabric sewed together along their margins to form a thin casing. To the upper surface of the casing is cemented a layer 4 of hard leather or other suitable material with a smooth, wear-resistant outer surface. The shape of the leather layers and of the metal layer is similar to the shape of a shoe sole but such layers are made wide enough 30 and long enough for the device to be used with soles of various widths and lengths.

The metal layer of my device is preferably made up of a single flat metal plate 14 for the heel portion, a single flat metal plate 5 for the 40 forepart and a series of transversely arranged sections 6 for the shank portion, the general outline of the metal layer as a whole being similar to the outline of a sole. As there is considerable pleating of the upper leather at the toe of the 45 shoe, it is preferable to insert an extra section or thickness 7 of metal at the toe portion. The front section of the metal layer is flat and the heel section is substantially flat and higher than the front section but the shank sections are preferably made with their sides to curve upwardly under pressure. The heel section is offset upwardly from the front section and the intermediate shank section slopes upwardly, all after the manner of the sole of a finished shoe. 50 55

The manner of using the device is as follows. My device is mounted on a stiffly resilient rubber block or cushion of the kind used in laying soles with the hard leather surface of my device uppermost. After the sole is stitched to the upper, the last, upon which the shoe was originally lasted (or one like it) is in the shoe and the shoe is then laid sole downward on my device. Pressure is then applied in any suitable way to press the sole against my device. As the work is thickest along the stitching and channel lips, the pressure will be greatest there as the front and heel portions of the metal, which are stiffly resilient, act, to a certain extent, after the manner of a solid block and it is desirable to make the front and heel portions of the work flat. As for the shank portion, the narrow strips of metal are more resilient so as to be able to conform to the shape of the shank of the sole both transversely and longitudinally. In actual practice, I have had very satisfactory results with blue steel spring metal of a thickness of $\frac{1}{32}$ of an inch made in sections of the shape indicated in the drawing.

The device hereinbefore described is particularly adapted to the type of shank wherein the surface curves continuously from side to side, as illustrated in Fig. 3. When it is desired to produce a shank with an angle along the middle portion thereof, I prefer to divide the metal layer lengthwise along the middle of the shank portion. In such case, the shank portion may be made with a single plate 9 on one side of the medial line and a single plate 10 on the opposite side of the medial line of shank, instead of using a multiplicity of narrow strips arranged transversely. In such case, the front ends of the shank pieces are substantially straight lines that extend obliquely forward and outward as shown in Fig. 7.

40 What I claim is:

1. A shoe leveling device comprising an upper layer and a lower layer of flexible material secured together to form a sole shaped casing, and a sole shaped layer of separate stiffly resilient metal plates secured in said casing, said metal layer comprising one stiffly resilient plate of the general shape of the forepart of the sole, a second stiffly resilient plate of the general shape of the heel portion and a plurality of separate resilient plates spaced apart throughout the shank portion.

50 2. A shoe leveling device comprising an upper

layer and a lower layer of flexible material secured together to form a sole shaped casing, a sole shaped layer of separate metal plates secured in said casing, and a layer of hard leather or other suitable material secured flatwise to the 5 top of said casing, said metal layer comprising one stiffly resilient plate of the general shape of the forepart of the sole, a second stiffly resilient plate of the general shape of the heel portion and a plurality of separate resilient plates spaced 10 apart throughout the shank portion.

3. A shoe leveling device comprising an upper layer and a lower layer of flexible material secured together to form a sole shaped casing, and a sole shaped layer of separate metal plates secured in said casing, the forepart of said metal layer comprising a stiffly resilient plate of the general shape thereof, the heel portion of said metal layer comprising a stiffly resilient plate of the general shape of said heel portion and the 15 shank portion of said metal layer comprising a plurality of relatively narrow resilient plates that extend from side edge to side edge of said metal layer.

4. A shoe leveling device comprising an upper 25 layer and a lower layer of flexible material secured together to form a sole shaped casing, and a sole shaped layer of metal secured in said casing, the shank portion of said metal layer comprising a plurality of relatively narrow separate 30 resilient plates that extend from side edge to side edge of said metal layer, and the front and heel portions being relatively wide flat plates.

5. A shoe leveling device comprising an upper 35 layer and a lower layer of flexible material secured together to form a sole shaped casing, and a sole shaped layer of metal secured in said casing, the shank portion of said metal layer being separate from the front and heel portions and comprising two separate plates on opposite sides 40 of said shank portion.

6. A shoe leveling device comprising an upper layer and a lower layer of flexible material secured together to form a sole shaped casing, a sole shaped layer of separate metal parts secured 45 in said casing, and a layer of hard leather or other suitable material secured flatwise on said upper layer, the shank portion of said metal layer being separate from the front and heel portions and comprising two separate plates on opposite 50 sides of said shank portion.

JOHN TWEEDIE.
